UNITED STATES PATENT OFFICE.

EDWARD CHESHIRE, OF PITTSBURGH, PENNSYLVANIA, ASSIGNOR TO MILLER SAW TRIMMER COMPANY OF MICHIGAN, OF PITTSBURGH, PENNSYLVANIA, A CORPORATION OF MICHIGAN.

SHEET-REGISTERING DEVICE.

1,135,766.

Specification of Letters Patent. Patented Apr. 13, 1915.

Application filed September 18, 1913. Serial No. 790,527.

To all whom it may concern:

Be it known that I, EDWARD CHESHIRE, a citizen of the United States, residing at Pittsburgh, in the county of Allegheny and State of Pennsylvania, have invented new and useful Improvements in Sheet-Registering Devices, of which the following is a full, clear, concise, and exact description, reference being had to the accompanying drawing, forming a part of this specification.

My invention pertains to sheet registering devices, and relates especially to automatic registering devices for use in connection with printing presses of what is known as the Gordon type.

In my Letters Patent No. 964,756 granted July 19, 1910, I have described and claimed a sheet registering device of the same type as that which forms the subject of the present invention; and it is one of the objects of the present invention to improve upon the device disclosed in the aforesaid Letters Patent.

It is another object of the invention to provide a registering device which, when used in connection with an automatic mechanism for feeding sheets to the press, will prevent the sheets from rebounding from the registering stops on the platen.

It is a still further object of the invention to provide a sheet registering device which will be simple in construction and efficient and certain in operation, which will be readily capable of adjustment for various sizes of paper and positions of the paper upon the platen, and which will not mar the surface of the paper in connection with which it is used.

A sheet registering device constructed in accordance with the present invention is described in the following specification and shown in the accompanying drawings. I wish it understood, however, that the invention may be embodied in other forms than that which is described and shown, and that changes may be made in the details of construction of the embodiment shown, without departing from the scope of the invention, as defined in the appended claim.

In the drawings: Figure 1 is a plan of the platen of a Gordon press having a sheet registering device constructed in accordance with my invention applied thereto. In this

figure the gripper fingers are shown raised to permit paper to be fed and the register arms are just receiving a sheet of paper. Fig. 2 is a fragmentary view of a similar nature to Fig. 1, showing the register arm which moves the sheet against the end and side stops. In this view the parts are shown in the position in which the sheet has been moved against the end stops and is about to be moved against the side stops, the gripper fingers being partly closed. The position of the parts when the sheet has been moved against the side stops is indicated in dotted lines in this figure. Fig. 3 is a side elevation of the parts shown in Fig. 2, in the corresponding full-line and dotted positions. Fig. 4 is a detail section taken on the line 4-4 of Fig. 3. Fig. 5 is a view of a similar nature to Fig. 2 but showing the register arm which pulls the sheets downward only. Fig. 6 is a perspective view of the bracket, which supports the register arm and associated parts shown in Fig. 5; Fig. 7 is a perspective view of the holder for the register arm shown in Fig. 5.

Like reference characters refer to like parts throughout the following specifications and the several figures of the accompanying drawings.

The device is illustrated as applied to the platen of a press of the Gordon type, the platen being indicated as 10 on the drawings. The platen is provided with the usual tympan-retaining bails 11, and end stops 12 against which the sheets of paper are adapted to be successively placed. A side stop 13 is also provided against which the side of the sheet engages when the sheet is in proper register. Pivoted to the platen is a gripper bar 14 which carries gripper fingers 15, the function of which is to retain the sheet in place during the printing operation and prevent the printed sheet from adhering to the type when the platen recedes from the bed. The above are among the ordinary equipments of a Gordon press.

The sheet registering device now to be described includes a registering arm which pulls the sheet first against the end stops 12 and then against the side stop 13, in the manner similar to that disclosed in my letters patent above referred to. In addition, a second registering arm is provided which

pulls the sheet against the end stops only, passing off the sheet before the first-named registering arm pulls the latter against the side stop. I will now describe the registering arm first named above.

Referring particularly to Figs. 1-4, 16 indicates a bracket which is secured to the edge of the platen by means of clamping plates 17 and 18 which engage over the edges 10 of one of the bails 11. Projecting upwardly and rearwardly from the bracket 16 is a lug 19 formed, at its upper end, with a bearing for receiving a pin 20. Rockably mounted on the pin 20 is a hanger 21 from the lower 15 end of which extends a hook 22. The hook 22 slidably engages around the gripper bar 14, so that the hanger 21 is caused to rock about the pin 20 when the gripper bar is rocked about its pivots.

20 The hanger 21 is provided, below the pin 20, with a pivot pin 23, which extends therethrough and enters a fork formed in a holder 24 for the registering arm 25. The pin 23 is secured in the fork by means of a vertical 25 pin 26; and it will be seen, therefore, that a universal connection is made between the holder 24 and the hanger 21. The registering arm 25 projects over the platen from the holder 24, and is held in place in the latter by means of a clamping piece 27 which may be loosened at will, to permit longitudinal adjustment of the registering arm for various sizes of sheets and various positions of the sheets upon the platen. At its front end, 30 the registering arm is formed with a fork having three tines, the center of which, 28, lies closely upon the tympan, and the outer of which, 29, are bent upwardly. A guard-plate 30 is secured to the bracket 16 so as to engage the upper face of the registering arm 25, thereby holding against the tympan at all times.

35 The holder 24 is provided with a laterally extending arm 31 which enters an elongated slot 32 formed in an upwardly extending flange 33, with which the clamping plate 18 is provided. When a sheet is fed to the platen its front edge, near one corner, enters above the tine 28 and below the tines 29, the sheet being thus crimped sufficiently to hold it impositively in connection with the registering arm. The sheet will then be substantially in position shown in Fig. 1. After 40 the sheet has thus been fed to the platen, and the latter begins to move to its printing position, the gripper bar 14 swings upwardly about its pivot, thus causing the hanger 21 to be moved to the left (Fig. 3), whereby the registering arm is pulled toward the edge of the platen, carrying with it the sheet against the end stops 12. Just after the registering arm has effected this, the parts being then 45 in the position shown in full lines in Figs. 2 and 3, the end of the arm 31 engages the left hand end of the slot 32; so that, during

the further movement of the gripper bar 14, the holder 24 is caused to swing about the pivot pin 26, the registering arm thus swinging toward the side stop 13 and carrying the sheet against the latter. By the time the 70 gripper bar 14 has completed its movement, the registering arm will have swung clear of the paper, as indicated in dotted lines in Fig. 2, leaving the sheet in engagement with the end stops 12 and side stop 13, and consequently in proper register.

75 The second registering arm operates in a substantially similar way to that described above, but it has no sidewise movement. Referring now particularly to Figs. 5 and 7, 34 80 indicates a two-part bracket adapted to be clamped, by means of a screw 36, to the edge of the platen, in such a position that the registering arm will operate upon the corner of the paper opposite to that which is operated upon by the registering arm described above. The bracket 34 is provided with an upwardly and rearwardly extending lug 35 to which is pivoted a hanger 37 having a gripper bar engaging hook 38, similar to the 90 hanger 21 and hook 22 described above. Passing through the hanger 37 is a pin 39 having secured thereto a holder 40 for the registering arm 41, the latter being adjustably secured in the holder by means of a reusable clamping piece 42. A guard plate 43 is secured to the bracket 34 and engages over the registering arm 41, thereby retaining it close against the platen at all times. The registering arm 41 operates similarly to 100 the registering arm 25 except that it has no sidewise movement, and its use insures that both corners of the sheet shall be brought into engagement with the end stops 12. During the time that the registering arm 25 is 105 moving sidewise, after having brought the sheet against the end stops, the registering arm 41 moves lengthwise out of engagement with the sheet.

110 In the use of automatic feeding mechanism in which the sheets are fed against stops upon a platen, it frequently occurs that the sheet will rebound from the stops, thereby becoming placed out of a proper registering position; and this is particularly so in the 115 case of mechanisms which run at high speed. By the use of the sheet registering device described above, this disadvantage is entirely obviated, since the sheet is fed into the jaws of the registering arm and retained therein, being subsequently pulled into the proper registering position. This renders the device especially useful in connection with automatic sheet feeding mechanisms.

120 Having thus fully described my invention, what I claim as new and desire to secure by Letters Patent, is:

125 The combination with a platen having an end stop and a side stop thereon, of a pair of sheet-receiving registering arms, means

for imparting to one of said registering arms a reciprocating movement solely toward and away from the end stop; and means for imparting to the other registering arm a movement first toward the end stop and then toward the side stop and return.

In witness whereof I have hereunto subscribed my name in the presence of two witnesses.

EDWARD CHESHIRE.
